UNITED STATES PATENT OFFICE.

EDWARD F. CROW, OF PLEASANTRIDGE, SOUTH DAKOTA.

STOCK-TANK HEATER.

Application filed June 25, 1924. Serial No. 722,378.

To all whom it may concern:

Be it known that I, EDWARD F. CROW, a citizen of the United States, residing at Pleasantridge, in the county of Perkins and State of South Dakota, have invented new and useful Improvements in Stock-Tank Heaters, of which the following is a specification.

This invention relates to stock tank heaters of the submergible type, wherein the heater is adapted to be placed within the tank with the major portion arranged beneath the level of the water, and used to maintain the water at a temperature to prevent freezing.

One of the chief characteristics of the present invention resides in the use of one or more water coils wholly disposed within the heater directly above the grate thereof, with the terminals of the coil opening at the sides of the casing to allow the water within the tank to pass through said coils, whereby the water is quickly heated for the purpose above mentioned.

Another important object of the invention resides in the provision of a heater equipped with air draft tubes, one of which is centrally disposed and susceptible of vertical adjustment, means being provided for supporting the adjustable draft tube in any given position, the tube being provided with a damper of any well known construction.

In carrying out the invention I also provide a supporting structure for the heater per se, the heater being suspended from an overhead support and capable of being conveniently lowered into the tank or raised therefrom, and supported in its elevated position when not in use.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view in elevation of the heater, certain of the parts being illustrated in section,

Figure 2 is a view taken on a right angle to Figure 1,

Figure 3 is a top plan view of the heater, showing the smoke stack in section,

Figure 4 is a transverse sectional view through the heater,

Figure 5 is a plan view of the base of the supporting structure.

Referring to the drawings in detail 10 represents a stationary base and forms part of the supporting structure for the heater per se. This base is preferably of rectangular contour in plan as clearly shown in Figure 5, while rising from two opposed sides of the base are parallel standards 11. The base 10 is further connected with these standards by means of wire brace elements, each including intermediate coil 12 receiving the adjacent standard 11, and divergently disposed limbs 13 having their extremities offset as at 14 to be received by openings formed in the adjacent side of the base 10. This structure is also shown in Figure 5. The standards 11 are connected at a point adjacent their upper ends by a transverse member 15 which has a central opening therein, and rising from this transverse member about the edge of said opening is a hollow tubular member 16 for a purpose to be hereinafter described. The upper extremities of the standards 11 terminate to provide spaced bearing 17 in 80 which is journaled a transverse shaft 18 formed at one end to provide a crank handle 19. Cables 20 are trained over the shaft 18, and under idle pulleys 21 journaled on the uprights 11 at points adjacent the lower ends thereof. The corresponding lower extremities of these cables 20 are connected to apertured lugs 22 carried by the casing of the heater per se, while the other extremities of the cables are connected to similar lugs 23 through the instrumentality of coil springs 24. These springs 24 being arranged in the length of the cable serve to maintain the latter taut. It will be noted upon inspection of Figure 3 that the apertured lugs 22 and 23 receive the standards 11, and are adapted to slide upon said standards when the heater per se is either lowered into the stock tank, not shown, or raised to an elevated position wholly above the tank.

The heater per se includes a casing 25 preferably of rectangular contour in cross section, which casing is equipped with a cover 26. This casing of course defines or provides a fire chamber in which is arranged 105

a grate 27 of any desired construction. Depending from the top 26 about the marginal edge thereof is a plurality of down draft tubes 28, which have their upper ends extending above the cover, and their lower ends extended inwardly beneath the grate as indicated at 29. Each draft tube 28 is supported by apertured lugs 30 projecting inwardly from the adjacent walls of the casing 25. The grate 27 is formed with lugs 27' which embrace the adjacent draft tubes 28, to which they are secured to assist in supporting the grate in a manner illustrated. The grate is further supported by webs 25 or lugs 29' rising from the inwardly extended portions 29 of the draft tubes 28 as shown in Figure 1. In addition to the draft tube 28 I also employ a central draft tube 31 which is vertically adjustable through an opening formed in the top or cover 26 of the heater. This central draft tube is equipped with a damper 32 at a point adjacent its upper end. The draft tube 31 is also arranged immediately adjacent and parallel with the smoke stack 33, the latter being provided with a vertical series of staples or the like 34 utilized to support the adjustable draft tube 31 in any given position. This tube 31 is formed with a hook 35 arranged to engage any one of the staples 34 supported by the smoke stack 33. Arranged within the casing 25 is one or more coils as clearly shown in Figures 1 and 2, the coils being arranged about the central draft tube 31, and have their extremities opening into the stock tank, which extremities pass through openings formed in the adjacent sides of the casing 25. The corresponding lower extremities 36 of the coils herein illustrated constitute the inlet ends of said coils, while the upper extremities 37 constitute the outlet coils. When the heater is submerged into the water contained in the stock tank, the water therein enters the coils 45 through the inlet ends 36 thereof, and after circulating within said coils returns to the tank through the outlet ends 37 of said coils. By reason of the fact that the coils are arranged immediately above the grate 27, the coils are subjected to the maximum heat of the fire adapted to be made within the grate

27, and consequently the water within the stock tank can be quickly heated from time to time with a view of maintaining the temperature of the water such as to prevent 55 freezing thereof, especially when the tank is exposed. The heater can be easily lowered within the tank when its use is desired by turning the crank handle 19 in one direction, and on the other hand it can be 60 easily elevated from within the tank by rotating the crank handle 19 in the other direction. When the heater is elevated, the smoke stack 33 passes through the tubular member 16 hereinabove referred to, while 65 the hooks 38 rising from the cover 26 of the heater is adapted to engage the cross member 15, to suspend the heater from said cross member or in other words support the heater in an elevated position. 70

While it is believed that from the foregoing description, the nature and advantages of the invention will be readily apparent, I desire to have it understood that I do not limit myself to what is herein shown and 75 described, and that such changes may be resorted to when desired as fall within the scope of what is claimed.

I claim:

A stock tank heater comprising a casing, 80 a closure therefor having openings therein, a grating arranged within the casing and spaced from the walls thereof, means for supporting the grate, down draft tubes depending from said closure and having 85 their upper ends projected through said openings, the corresponding lower ends of said tubes being directed inwardly and arranged immediately beneath the grate, eye members holding said tubes associated with 90 the casing, a draft tube depending centrally from said closure and having its upper end projecting above the closure, said casing having spaced openings at the opposite sides thereof, water heating coils surrounding the 95 last mentioned tube and arranged within the casing, the free ends of each coil projecting through the adjacent openings in one side of the casing, and a smoke stack rising from the casing.

In testimony whereof I affix my signature.
EDWARD F. CROW.
